UNITED STATES PATENT OFFICE.

PAUL BILLY, OF LINDEN, NEW JERSEY.

LIFE-PROTECTOR.

1,350,136.

Specification of Letters Patent. Patented Aug. 17, 1920.

Application filed April 14, 1920. Serial No. 373,836.

To all whom it may concern:

Be it known that I, PAUL BILLY, a citizen of the United States of America, residing at Linden, in the county of Union and 5 State of New Jersey, have invented certain new and useful Improvements in Life-Protectors, of which the following is a specification.

The primary object of the invention is the 10 provision of a safety device adapted for ready attachment to a window for the assistance of workmen in carrying on their labors outside of the window the device being serviceable in washing windows as well as 15 pairing a window casing or sill or an adjacent portion of the building.

A further object of the invention is to 20 provide a device that is easy and inexpensive to manufacture and is readily attached to the lower sash of a window for vertical adjustment therewith the same possessing great strength and being readily detached when not in use.

With these general objects in view the invention consists of the novel combination 25 and arrangement of parts hereinafter more fully described in connection with the accompanying drawing, and in which like reference characters designate corresponding parts throughout the several views.

In the drawings,

Figure 1 is an elevational view of an exterior portion of a house showing my invention operatively mounted upon a window 30 thereof,

Fig. 2 is a vertical sectional view of the same illustrating by dotted lines, the lower sash in an elevated position with a spacing member therebeneath in the window frame,

40 Fig. 3 is a perspective view of one of the attaching plates at an upper corner of the window sash a portion of the latter being illustrated by dotted lines,

Fig. 4 is a vertical sectional view through 45 the upper portion of a sash provided with a modified form of plate,

Fig. 5 is a top plan view thereof,

Fig. 6 illustrates a pair of foldable spacers for employment in the window casing 50 and

Fig. 7 is an elevational view of one of the spacers in its folded position.

Referring more in detail to the drawings, my invention broadly consists of channel 55 plates 10 adapted for attachment adjacent the upper corners of the lower sash such as

11 to a window, the latter having a casing 12 mounted in the building wall 13 with an upper sash 14 as well as the lower sash 11 60 slideable in said casing 14, a holding member 15 being attached to the said plates 10.

Each plate 10 is of channel formation for fitting over the corner portion of the sash 11 with an inwardly inclined leaf 16 having a transverse slot 17 for the reception of the buckle-carried ends 18 of the holding member 15 which in this embodiment of the invention comprises two straps with a belt or girdle 19 at the lower ends of said straps. A rear leaf 20 of the plate 10 engages the 70 inner face of the sash 11 while screws 21 are secured through the upper or body portion 22 of said plate for engaging in the upper rail 23 of said sash 11. A semi-tubular guide 24 depends from the end of the 75 body portion 22 within a correspondingly cut-out portion of the sash 11 adapted for receiving the usual window-rope or cord 25 passing upwardly through the guide 24 from the point of attachment to the 80 window sash as at 26.

The strap ends 18 are readily detached from the leaves 16 when desired, and are again connected thereto for use by lowering the upper sash 14 and elevating the 85 lower sash 11 bringing the plates 10 in a readily accessible position from a point within the building, the leaf 16 of each plate being preferably countersunk in the sash 11 permitting free relative movements 90 of the sashes. The plates 10 are permanently carried by the lower sash 11 and neither obstructs the vision materially or detracts from the appearance or usual operation of the window in opening and closing 95 while the guides 24 form metal guards for the window cords 25.

A modified form of construction of the attaching plate is shown in Figs. 4 and 5 and comprises an angle iron or plate 27 100 upon the upper inner edge of the lower sash 11', holdfast devices 28 passing therethrough into the upper rail 23' of said sash. A leaf 16' for attaching the supporting member outwardly of the sash and window 105 is adjustably mounted upon the plate 27 by stud bolts 29 adjustably extending through slots 30' in a body portion 22' of said leaf 16', the said bolts being secured through the plate 27 and into the top of the rail 23'. 110

An arcuate cord guide 24' depends from the outer end of the said body portion 22'.

Foldable spacers for insertion within the window casing 12 as illustrated by dotted lines in Fig. 2 of the drawings consist of bars 30 connected together by hinges 31 with pins 32 upon the ends thereof for reception in sockets 33 in the bottom or sill 34 of the window frame 12. When two or more of the spacers are employed leaf springs 35 carried by alternate bars 30 are positioned 10 between the spacers.

The complete operation of the device will be apparent from this detailed description thereof, the manner of attaching the buckled strap ends 18 to the plate leaves 16, having been set forth, and it being understood that a similar manner of attaching the holding member 15, to the leaves 16' is also employed, the last-named leaves having transverse receiving slots 17.

20 A person desiring to wash the panes 36 of the sashes 11 and 14 attaches the holder 15 to the plates and positions the belt 19 around his waist while standing upon the window ledge 37. When desiring to maintain the holder 15 at a higher elevation, the spacers 30 are positioned beneath the lower sash within the casing 12 as illustrated by dotted lines in Fig. 2 of the drawings.

In this manner, a workman either repairing or cleaning parts of the window or building is insured against accidental injury by falling to the ground when employing my invention. A safety device is provided which is readily positioned for use 30 when desired and assists in strengthening the corner portion of the window sash 11 after the manner of a combined bracket and cord guide at all times when the plate members of the device are in position upon the window sash.

40 While the form of the invention herein set forth is believed preferable it will be understood that minor changes may be made therein without departing from the spirit 45 and scope of the invention as claimed, and the device is also serviceable for other uses, such as, assisting a person in hanging out a washing and also in the event of a fire in the building.

50 What I claim as new and desire to secure by Letters Patent, is:—

55 1. A device of the class described comprising an angular plate adapted to be secured to the upper corner of a window sash with a leaf thereof projecting at an angle inwardly of the sash and a semi-tubular guide depending therefrom adapted for the reception of the window cord therethrough when the device is in use.

60 2. A device of the class described comprising an angular plate adapted to be secured to the upper corner of a window sash with a leaf thereof projecting at an angle inwardly of the sash, a semi-tubular guide 65 depending therefrom adapted for the recep-

tion of the window cord therethrough when the device is in use, holding straps detachably connected to said leaves and a belt carried by said straps.

3. An attaching member adapted to be 70 secured to the upper corner of a window sash comprising a channel plate embracing the upper rail of the sash and having an angularly projecting leaf extending toward the center of the sash when the device is in 75 position, a semi-tubular guide depending from the outer end of said plate adapted for countersunk engagement within the end rail of a sash for the guiding reception of the sash cord through said guide and means 80 for attaching said plate to a window-sash.

4. An attaching member adapted to be secured to the upper corner of a window sash comprising a channel plate embracing the upper rail of the sash and having an angularly projecting leaf extending toward the center of the sash when the device is in position, a semi-tubular guide depending from the outer end of said plate adapted for countersunk engagement within the end rail of 85 a sash for the guiding reception of the sash cord through said guide, means for attaching said plate to a window-sash, the said leaf having a transverse slot therein and a body holding member detachably engaging 90 said leaf through said slot.

5. In combination with a window sash, channel plates attached to the upper corners thereof having inwardly projecting leaves outwardly of the sash provided with 100 receiving slots, depending guides at the ends of the plates countersunk within the end rails of the sash adapted for the reception of the sash cord when the sash is mounted within the window frame, said guides being 105 arcuate in cross section and securing means between said plates and sash.

6. In combination with a window sash, channel plates attached to the upper corners thereof having inwardly projecting leaves outwardly of the sash provided with receiving slots, depending guides at the ends of the plates countersunk within the end rails of the sash adapted for the reception of the sash cord when the sash is mounted 110 within the window frame, said guides being arcuate in cross section, securing means between the said plates and sash, straps detachably connected through the slots of said leaves and a body attaching belt carried by 115 said straps.

7. An article of manufacture comprising a channel plate having one of its side leaves obliquely projecting from the intermediate body portion and provided with a slot and a 120 channelled cord guide perpendicularly projecting from one end of the body portion of the plate at the same side thereof as the leaves of the plate, the oblique leaf extending 125 away from the said guide.

8. An article of manufacture comprising
a channel plate having one end of its side
leaves obliquely projecting from the inter-
mediate body portion and provided with a
5 slot and a channeled cord guide perpendicu-
larly projecting from one end of the body
portion of the plate at the same side there-
of as the leaves of the plate, the oblique leaf
extending away from the said guide, and
10 a body-supporting member detachably se-
cured through said slot.

9. A device of the class described com-
prising a window sash, an angle plate se-
cured to the upper rail thereof, an angular
supporting member adjustably mounted 15
upon said upper rail of the sash overlying
the upper portion of said angle plate and
a cord guide depending from the outer end
of the upper portion of said angular sup-
porting member.

In testimony whereof I affix my signature.
PAUL BILLY.
